UNITED STATES PATENT OFFICE.

WILLIAM FONDILLER, OF NEW YORK, N. Y., ASSIGNOR TO WESTERN ELECTRIC COMPANY, INCORPORATED, OF NEW YORK, N. Y., A CORPORATION OF NEW YORK.

LOADING UNIT FOR TELEPHONE SYSTEMS.

1,253,365.

Specification of Letters Patent. Patented Jan. 15, 1918.

Application filed December 30, 1916. Serial No. 139,984.

To all whom it may concern:

Be it known that I, WILLIAM FONDILLER, a citizen of the United States, residing at New York, in the county of New York and State of New York, have invented certain new and useful Improvements in Loading Units for Telephone Systems, of which the following is a full, clear, concise, and exact description.

10 This invention relates to loading units for telephone systems, and particularly to core structures for a loading unit adapted for the simultaneous loading of two physical circuits and their derived or phantom circuit. 15 In an arrangement described and claimed in an application of J. B. Speed, Serial No. 88,072, filed March 31, 1916, and assigned to the same assignee as the present application, the simultaneous loading of two physical circuits and their derived phantom circuit is provided for by means of a loading unit characterized by two toroidal core members intersecting on a common diameter. In said loading unit, the two line windings 20 individual to one of the physical circuits are located on opposite halves of one toroid, and the line windings individual to the other physical circuit are located on opposite halves of the other toroid. Each physical 25 circuit is thus loaded independently of, and without interference with, the other physical circuit. Furthermore, when phantom circuit currents flow through the windings of this loading unit, the distribution of flux is 30 such as to load the phantom circuit in addition to the physical circuits.

It is an inherent characteristic of a loading unit of the kind just described that the mutual inductances between all line windings 40 are very nearly equal, as a result of which the phantom circuit inductance is only fifty per cent. of the physical circuit inductance. This is due to the fact that for phantom circuit operation the two line windings 45 of each toroid are connected in parallel and the two parallel circuits thus formed are connected in series. The resultant inductance therefore is equal to that operative in a single line winding; that is, the self-inductance of a line winding plus its mutual inductance to an adjacent winding. The mutual effects of the remaining windings being 50 in opposite directions cancel each other. The physical circuit inductance on the other hand 55 is that due to two line windings in series,

which in effect is the sum of the two self-inductances plus twice their mutual inductance. It has been found in practice, however, taking into consideration the mutual capacity of the phantom circuit as compared with the mutual capacity of the physical circuit, that, in order to load a phantom circuit to the best advantage, its inductance should be approximately sixty per cent. of the physical circuit inductance.

60 In a patent to George A. Kelsall, No. 1,238,153, dated August 28, 1917, and assigned to the same assignee as the present application, an improvement upon the invention covered by the application of James 65 B. Speed, hereinbefore mentioned, is described and claimed. Said Kelsall invention has for its general object to modify the relation of the physical circuit inductance to the phantom circuit inductance, so that the latter is approximately sixty per cent. of the former, thereby satisfying the requirement before mentioned; and said invention is characterized by the provision in the magnetic structure of gaps of high reluctance 70 which are so located that they increase the reluctance of the paths traversed by the physical circuit flux, but do not substantially increase the reluctance of the paths traversed 75 by the phantom circuit flux.

80 The present invention may be considered an improvement upon the inventions covered by the aforesaid applications of J. B. Speed and G. A. Kelsall; and is characterized by the provision in the magnetic structure of 85 gaps of high reluctance in the form of slots extending diagonally across the core members at their points of juncture. Among the advantages of this structure over the structures described and claimed in said 90 Kelsall application, are decreased susceptibility of the phantom circuit to the effects of superimposed telegraph currents and greater ease in obtaining the desired ratio 95 between physical circuit inductance and phantom circuit inductance. The first mentioned advantage is due to the fact that in this structure a gap is interposed in the path of the phantom circuit flux as well as in the path of the physical circuit flux.

100 The invention will be understood from the following description taken in connection with the accompanying drawing, in which Figure 1 is a perspective view of the magnetic structure of a loading unit embodying one 105

110

form of the invention; and Fig. 2 is a perspective view of another form of magnetic structure also embodying the invention.

The core members shown in Figs. 1 and 5 2, and hereinafter described, may be of any suitable magnetic material. For example, they may conveniently be formed of finely divided iron, the individual particles of which are insulated from one another, the 10 core material being molded by high pressure, in the manner described and claimed in an application for patent of James B. Speed, Serial No. 89,409, filed April 6, 1916, and assigned to the same assignee as the 15 present application. Such core material may be readily worked to the desired shapes by molding and cutting.

Referring to Figs. 1 and 2, the core structures for loading units therein shown comprise in effect two toroidal core members 1 20 and 2 arranged to intersect at right angles on a common diameter. It will be understood that opposite halves of core member 1 are intended to carry windings included 25 in the line conductors of one physical circuit; and that the opposite halves of core member 2 are intended to carry windings included in the line conductors of the other physical circuit; as described in the aforesaid 30 application of J. B. Speed, Serial No. 88,072. It will also be understood that the parts may be held together in any suitable manner.

In the core structure of Fig. 1, gaps of 35 high reluctance are provided in the form of slots extending diagonally across the core members 1 and 2 at their points of juncture, said slots being in planes substantially at right angles to one another. Said slots may 40 be filled with any suitable non-magnetic material such as blocks or sheets of fiber 3 and 4.

In a core structure shown in Fig. 2, the 45 gaps of high reluctance located at the points of juncture of the core members 1 and 2, are in the form of crossed slots extending diagonally across said core members. Said slots may be filled with non-magnetic material, such as fiber of the form indicated at 5 and 6.

As explained in the aforesaid application 50 of J. B. Speed, Serial No. 88,072, the physical circuit flux due to windings on core member 1 threads and is confined to that core member; and the physical circuit flux due to windings on core member 2 threads and 55 is confined to that core member. And the phantom circuit flux due to said windings all passes from one point of juncture through the two halves of core member 1 to the other juncture, and back through the two halves 60 of the other core member 2 to the first men-

tioned juncture. In Figs. 1 and 2, the paths of the physical circuit flux are indicated by arrows made with full lines; and the paths of the phantom circuit flux are indicated by arrows made with dash lines.

It will be obvious from the foregoing description and from the drawing, that the gaps of high reluctance of the two forms shown will increase the reluctance of the 65 paths traversed by the physical circuit flux to a much greater extent than they will increase the reluctance of the paths traversed by the phantom circuit flux, thereby reducing the mutual inductances of the physical circuit more than those of the phantom circuit. By suitably proportioning said g 70 it is possible to make the reluctance of path traversed by the phantom circuit flux such that the inductance operative in the phantom circuit is substantially sixty per cent. of that operative in each of the physical circuits, which is the relation desired as hereinbefore explained.

It will be understood that while in the 75 drawing core structures are shown in which the core members are substantially square in cross-section, they may, if desired, have other cross-sectional forms. The term "toroid" used herein, is intended to refer to a ring of any desired cross-section. It will 80 also be understood that instead of rings, rectangular or other forms of frames and closed figures might be employed, and that, for want of some broader expression, the term "toroid" is used to denote all such 85 structures.

What is claimed is:

1. A loading unit having a plurality of core members each in the form of a closed figure, said members intersecting at a plural- 100 ity of points and being provided with gaps of high reluctance in the form of slots extending diagonally across said members at the intersections.

2. In a loading unit, two toroidal core 105 members intersecting on a common diameter and having gaps of high reluctance therein in the form of slots extending diagonally across said members at their points of juncture.

3. In a loading unit, two toroidal core 110 members intersecting on a common diameter and having gaps of high reluctance therein in the form of crossed slots extending diagonally across said members at their points of 115 juncture.

In witness whereof, I hereunto subscribe my name this 29th day of December A. D., 1916.

WILLIAM FONDILLER.
